UNITED STATES PATENT OFFICE

BERNARD SHREIBER, OF NEW YORK, N. Y., ASSIGNOR TO MEYER GENDEL, OF NEW YORK, N. Y.

OIL PUMP

Application filed February 11, 1931. Serial No. 515,116.

This invention relates to fuel oil burner apparatus such as is used in connection with a burner nozzle for supplying oil and air thereto.

5 One important object of the invention is to provide a novel arrangement of pumps, piping and the like in such an apparatus whereby to produce a highly efficient operation.

A second important object of the invention 10 is to provide, in such an apparatus a means for atomizing or emulsifying oil prior to its being fed to the burner.

A third important object of the invention 15 is to provide a novel emulsifying pump for such apparatus.

A fourth important object of the invention is to provide a novel arrangement of parts wherein the emulsifying pump will be jacketed with oil in the passage of the oil to the 20 pump for emulsification so that the oil will be warmed and thus rendered easy to emulsify.

With the above and other objects in view, the invention consists in general of certain 25 novel details of construction and combinations of parts hereinafter fully described, illustrated in the accompanying drawings and specifically claimed.

In the accompanying drawings like characters of reference indicate like parts in the 30 several views, and:—

Figure 1 is a right side elevation of the apparatus.

Figure 2 is a left side elevation thereof.

35 Figure 3 is a front elevation of the emulsifier.

Figure 4 is a vertical axial section through Figure 3.

40 Figure 5 is a longitudinal axial section through the nozzle.

Figure 6 is a similar section through the by-pass pressure valve.

45 Figure 7 is an end elevation of the oil needle-valve.

Figure 8 is a vertical axial section through Figure 7.

In the embodiment here illustrated, which 50 shows one preferred form of the invention, there is provided a stand or base 10 and cen-

trally of this stand is mounted an ordinary electric motor 11. On the stand is a junction box 12 for connection of the electric wiring leads (not shown) and from this junction box a cable 13 extends to the motor 11.

On the forward end of the stand is an emulsifier having a cylindrical casing 14 through which extends an annular channel 15 opening rearwardly of the emulsifier. Within this

casing 14 is a cylindrical chamber 16 wherein is eccentrically positioned a cylindrical impeller 17 having vanes or blades 18 sliding in channels 19 in the impeller body and, in operation, having their outer edges engaging against the cylindrical wall of the chamber

16. The forward end of the chamber 16 is closed by a head 20 having at its lower part an intake port 21 and an exhaust port 22, these ports being laterally spaced to lie on opposite sides of the lower part of the impeller 17. The rear ends of the chamber 16 and channel 15 are closed by a head 23 which has, at its lower part, an intake port 24 and at its upper part, an outlet port 25. The head

20 carries an end bearing 26, and the head 23 carries a through bearing 27 provided with a packing gland 28, these bearings and the impeller being axially aligned with the motor

11 so that the motor shaft 29 may extend through bearing 27 and impeller 17 and into bearing 26. The impeller is suitably secured to the motor shaft to be driven thereby.

A supply line 30 provided with a valve 31 leads from a suitable source of oil supply such as a tank or reservoir (not shown) to the port 24 and a pipe 32 leads from the port 25 to the intake connection at the upper part of an ordinary strainer 33 which has its outlet connected to the intake of a standard pump

34. This pump is driven from the shaft 29 and the construction of the pump and strainer being standard their details are not here shown. A delivery pipe 35 leads from the pump outlet to a T-fitting 36 and from the forward end of this T-fitting a pipe 37 leads

30 through a strainer 38 to a magnetic oil valve 39 of standard construction, this valve being of the type which automatically closes upon interruption of current to the motor and being connected to the junction box by a cable

40. The strainer has a cleanout normally closed by a plug 41. A pressure gage 42 is connected to the pipe 37. The rear end of the T-fitting 36 is connected to the by-pass pressure valve illustrated in detail in Figure 6. 5 This valve has a T-body 43 the forward end of which is connected by a suitable nipple with the T-fitting 36. The stem or outlet of this body is threaded for connection to a pipe 44 leading back to the oil supply and provided with a valve 45. Immediately above the outlet is a valve chamber 46. And to the rear of this chamber is an internally threaded portion 47 terminating rearwardly in a stuffing box 48. In this threaded portion is screwed a spring seat 49 having a stem 50 which passes through the stuffing box and is provided with a screw kerf or analogous part so that the spring seat may be screwed in and out and thus adjusted. The seat and stem are chambered forwardly to receive the stem 51 of a valve head 52 which seats on the rear end of the intake of this valve. A cap 53 normally conceals the kerf provided end of the 25 valve stem and a spring 54 surrounds the stem between the valve head and spring seat. By this means excess oil delivered by the pump will by-pass back to the reservoir and the desired oil pressure in the pipe 37 will not be exceeded, proper adjustment to this end being made of the spring seat 49.

30. From the valve 39 leads a pipe 55 which communicates with the needle valve 56 by which the admixture of oil and air is regulated. This needle valve shown in Figures 7 and 8 consists of an inverted T-shaped body 56 having a nipple 57 projecting from the stem of the T for connection of the pipe 55. At the lower end of the stem is a valve seat 58 40 with which cooperates an adjustable needle valve 59 having a stem 60 projecting upwardly through a capped stuffing box 61 and provided with a suitable head to permit turning of the valve and adjustment thereby with 45 relation to the seat 58. One end of the body 56 is screwed into the inlet opening 21 and an air intake pipe 62 is attached to the other end of the body and is provided with an air muffler 63 of standard construction. Leading forwardly from the outlet 22 is a pipe 64 which carries on its forward end a nozzle 65 provided, as in Figure 5 with a replaceable jet tip 66. A pressure gage 67 is connected to the pipe 64.

50. The course of the oil and air is indicated by the arrows on Figures 1 and 2 and it will be seen that, as the oil enters the apparatus, it flows first around the emulsifier. It is a well known physical law, exemplified by Joule's 55 experiment showing the relationship between heat and energy, that the movement of an impeller through fluid will raise the temperature of the fluid. Consequently, the oil in the channel 15 will be warmed by the action of the emulsifier and will flow readily through

the pump and its connections to the emulsifier where an emulsion of air and oil will be formed and delivered through the nozzle in the form of a fine mist. The emulsifying chamber will be kept cool by the flow of oil 75 through channel 15.

There has thus been provided a simple and efficient device of the kind described and for the purpose specified.

It is obvious that changes may be made in 75 the form and construction of the apparatus without departing from the principles involved. It is not, therefore, wished to confine the invention to the exact form and arrangement here shown but it is wished to include all such as come within the scope claimed.

Having thus described the invention, what is claimed as new, is:—

1. In an oil burning apparatus, a pump having a central chamber therein surrounded by an unbroken annular wall and having an oil jacket entirely surrounding the periphery of the central chamber concentric thereto to form an annular oil-heating chamber, a beater mounted eccentrically in said chamber to provide a lunate oil space between the beater and the adjacent annular chamber wall, said beater having movable vanes constantly contacting with said annular chamber wall, said central chamber having inlet and outlet ports at one end extending axially of the beater and opening into respective ends of the lunate passage, said oil jacket also having inlet and outlet ports, and conduit means connecting the outlet port of the oil jacket and the inlet port of the central chamber.

2. In an oil burning apparatus, a pump having a central chamber therein and having an annular oil jacket entirely surrounding the periphery of the central chamber concentric thereto to form an annular pre-heating chamber, a beater mounted eccentrically in said chamber to provide a lunate oil space between the beater and the peripheral chamber walls, said beater having movable vanes constantly contacting with said peripheral chamber wall, said central chamber having inlet and outlet ports at one end and opening into respective ends of the lunate passage, said oil jacket also having inlet and outlet ports, and conduit means connecting the outlet port of the oil jacket and the inlet port of the central member, the ports for the oil jacket being located at the end opposite the ports for the chamber, the inlet port for the jacket being located at the bottom of the jacket and the outlet port of the jacket being located at the top thereof.

In testimony whereof I affix my signature.

BERNARD SHREIBER.
